DENNIS CHURCH, OF ROCHESTER, NEW YORK, ASSIGNOR TO M. D. KNOWLTON COMPANY, OF ROCHESTER, NEW YORK, A CORPORATION OF NEW YORK.

MACHINE FOR CUTTING CORRUGATED PAPER-BOARD.

1,055,610.

Specification of Letters Patent.

Patented Mar. 11, 1913.

Application filed November 30, 1908. Serial No. 465,326.

To all whom it may concern:

Be it known that I, DENNIS CHURCH, citizen of the United States, and resident of Rochester, in the county of Monroe and State of New York, have invented certain new and useful Improvements in Machines for Cutting Corrugated Paper-Board, of which the following is a specification.

This invention relates to a machine for cutting materials of various kinds and especially corrugated paper board, etc., and the main object of the invention is to provide a cutting machine for slotting and other purposes, which will cut easily and smoothly materials, such as corrugated paper board, which it has been difficult to cut smoothly with knives or other devices having straight cutting or shearing edges.

I have found that materials such as corrugated paper board, which will usually be crushed down by ordinary straight-edged cutters or knives, can be easily and smoothly cut when the edges of the cutting knives are so formed as to puncture or perforate the material to the proper extent before the material is completely severed along a given line by the cutting or shearing edge of the knife. In obtaining the desired result means is employed for puncturing and severing the corrugated paper board or other material along a line common to the punctures and the line of division, the preferred means employed for the purpose being a cutter having an irregular edge constituting both a puncturing and a cutting element. As a shearing cut is the best, in practice, for cutting off or for slotting material of this character, my improved cutter, in the preferred form, has a shearing edge capable both of puncturing and shearing the material, the two functions being performed in practice by a cutter having a serrated or toothed edge.

In the drawings a slotting machine illustrating one embodiment of the invention is shown, Figure 1 being a perspective view of such a machine, Fig. 2, an enlarged sectional detail illustrating one of the toothed cutters and cooperating parts, and Fig. 3 a plan of the slotted fixed element of the cutting means shown in Fig. 2.

Similar characters designate like parts in all the figures of the drawing.

The slotting machine illustrated in Fig. 1 is or may be in most respects of well-known

construction, and as shown embodies the usual bed 2 supported on legs 3, said bed having vertical guides at opposite ends thereof in which work slide-rod, such as 4, secured to the ends of a cross-head 5 carrying the cutter or cutters of the machine. This cross-head is illustrated as operated also in a well-known manner, to wit, by eccentrics and eccentric-rod connections, such as 6 and 7, the eccentrics being carried by a main driving shaft, such as 8, at one end of which are the usual fast-and-loose pulleys 9 and 10, suitable belt-shipping means, designated generally by 11, being employed in connection therewith and operated from a rock-shaft 12 by a shipping-lever 13. The construction and operation of all of these parts is well understood.

The cross-head 5 is so formed in a slotting machine of this kind as to permit the attachment thereto and adjustment lengthwise of the cross-head of a plurality of cutters disposed transversely thereto. A dovetailed guide 14 is illustrated as depending from said cross-head for this purpose. To this guide on the cross-head the cutter or cutters will be secured, preferably by wedging devices, such as illustrated at 15 and 16, for holding the cutters firmly in place. In a slotting machine such as that illustrated these cutters are identical in construction and they are designated generally by 17. Each of these movable cutters cooperates with a fixed slotted cutting edge, such as 18, which may be formed in a part 19 adjustable on ways on the bed in a well-known manner, the movable cutter preferably having at the beginning of its cutting edge an extension 20 for locating or centering the cutter with respect to the walls of the slot 18.

The working edge of the movable cutter is, as shown, inclined so as to shear the material, and is of irregular outline when viewed from either end of the machine. It is so formed as to both puncture or perforate and cut or shear the material on which the cutter is to work. This material, such as corrugated board, will thus be perforated in the cutting line before the material is completely severed along that line. By making the puncturing or perforating device in the form of saw-teeth these perforations will be formed gradually and gradually increased in length until they meet and form a continuous cutting line. Thus

such material as corrugated board will be first punctured or perforated at a point or points of slight resistance and the openings made by puncturing will gradually be increased in the same manner by the saw-teeth, a minimum of resistance being thereby opposed by the corrugated board to the cutting action, instead of the maximum resistance which is opposed when a substantially straight-edged cutter is brought down on the tops of the arches of the corrugations.

The cutting edges of the movable cutters 17 are designated generally by 21, and the puncturing or perforating portions thereof, here shown as saw-teeth, are designated by 22. It will be noticed that the size of the teeth 22 decreases from the beginning to the end of the cutting edge of the movable cutter. Such a cutter when brought down on the corrugated board operates to puncture or perforate the arched portions of the corrugations gradually and reduce the resistance thereof to the action of the cutter, the action both in puncturing and in severing being a gradual and progressive one extending from the beginning to the end of each cutting edge, because of the inclination of such edge, and also because of the gradual decrease in the size of the teeth. In certain aspects of my invention it is essential that both side edges of each V-shaped cutting tooth be similarly sharpened, and the axes or median lines of said V-shaped teeth should be approximately at right angles to the stationary cutter as the respective teeth of the movable cutter contact with and begin to pierce the material to be severed.

By means of cutters of the type described, corrugated board and other fibrous material is cut cleanly and with the least resistance to the action of the movable cutters. Moreover, it will be clear that a cutter of such type permits of the use of a cutter blade of indefinite length having little or no angle to the opposing fixed cutter and consequently requiring only a minimum length of stroke, *i. e.*, a stroke sufficient merely to provide for proper clearance of the work. The reason for this is, that the necessary or desired angle of shear, which is a considerable one to cut fibrous stock easily and cleanly, is obtained by the toothed or serrated formation of the cutting edge of the cutter blade which provides the series of cutting edges 21 having the desired angle with respect to the opposing or fixed cutter. Furthermore, with this type of cutter the stroke of the machine need never be changed with increase or decrease of the length of slot or cut which has to be produced at one stroke of the cutter, because the angle of the cutting edges 21 to the opposing cutter 18 may be varied to suit different conditions, and this may be done

merely by proper grinding of said edges or otherwise. The short stroke of the machine permitted by use of the described type of cutter also makes it possible to use a simple, light, compact and high-speed machine to do the same work heretofore done by a much larger and heavier machine having a cutter with a straight cutting edge and consequently operating with a much longer stroke.

Suitable means may be provided, as is usual, for gaging the position of a sheet or strip of material to be cut or slotted and for preventing the material being carried up on the ascent of the cross-head 5. Gages are illustrated at 23 for the purpose of locating the material in its proper position to permit it to be cut or slotted the desired distance from one edge, and the usual strippers 24 are provided at opposite sides of the slots 18 for clearing the cutters by holding the material down when the cross-head ascends. Both the gages 23 and the strippers 24 are adjustable, as are the movable cutters 17, the gages being adjustable cross-wise of the head 5 while the strippers and the fixed and movable cutters are adjustable in a direction lengthwise of the cross-head.

While I have shown and described one desirable embodiment of my invention, I do not wish to be understood as confining myself to the particular form thereof which I have disclosed, for it is obvious that the same may be variously modified without departing from the principle of my invention, and as all such obvious changes and modifications are within the purview of my invention, I do not limit myself to anything shown and described except so far as I may be limited by the prior art to which the invention belongs.

What I claim is:

1. In a machine for cutting corrugated paper board and the like, the combination of a substantially horizontal bed having a straight edged stationary knife on which the paper board is laid, a knife movable downward to coöperate with said stationary knife, and having a saw toothed cutting edge formed of a plurality of V-shaped teeth each of which is similarly sharpened along both side edges, and power operated means to so operate said movable knife that its saw toothed edge, as it contacts with the paper board, is arranged at an angle to the latter and to the stationary knife so that one end portion of the toothed edge begins to cut before the other end portion, whereby the paper board or the like is simultaneously punctured and sheared at successive points along the cutting line.

2. In a cutting machine, the combination of two coöoperating cutters, one of which is movable in a path substantially at right angles to the other, one of said cutters be-

ing provided with a saw-toothed cutting edge arranged at an angle to the cutting edge of the other said edge formed of V-shaped teeth similarly sharpened on both edges, and the teeth of said toothed edge gradually decreasing in size from end to end, as described.

3. In a cutting machine, a cutter having a straight cutting edge, and a second cutter movable at right angles to said first named cutter and provided with a saw-toothed cutting edge arranged, as a whole, at an inclination to the straight cutting edge of the first named cutter, the saw-teeth which begin the cut being of larger size than those at the opposite end of the toothed edge.

4. In a machine for cutting corrugated paper board and the like, the combination of a substantially horizontal bed having a stationary knife on which the paper board is laid, a knife movable downward to co-operate with said stationary knife and having a cutting edge formed of a plurality of V-shaped teeth each of which is similarly sharpened along both side edges, and means to so operate said movable knife that its aforesaid cutting edge, as it contacts with the paper board, is arranged at an angle to the latter and to the stationary knife, whereby the paper board or the like is simultaneously punctured and sheared at successive points along the cutting line.

5. In a machine for cutting corrugated paper board and the like, the combination of a substantially fixed bed having a stationary knife on which the paper board is laid, a knife movable downward to co-operate with said stationary knife and having a cutting edge formed of a plurality of V-shaped teeth the side edges of which are

similarly sharpened, and means to so operate said movable knife that its aforesaid cutting edge, as it contacts with the paper board, is arranged at an angle to the latter and to the stationary knife so that one end portion of said cutting edge begins to cut before the other end portion, the median lines or axes of said teeth being directed approximately at right angles to the stationary knife as the respective teeth contact with and pierce the paper board or other material.

6. In a machine for cutting corrugated paper board and the like, the combination of a substantially horizontal bed having a stationary knife on which the paper is laid, a vertically movable cross head above said bed, and a knife secured to said cross head and movable downward therewith to co-operate with said stationary knife, said movable knife having its cutting edge directed at an angle to the cutting edge of the stationary knife, and the cutting edge of said movable knife being formed by a plurality of V-shaped teeth similarly sharpened along both side edges and progressively increasing in size toward that end of the movable knife which first contacts with the paper board or other material, the median lines of said teeth being approximately at right angles to the stationary knife.

Signed at Rochester, in the county of Monroe, and State of New York, this 16th day of November, A. D. 1908.

DENNIS CHURCH.
